UNITED STATES PATENT OFFICE.

FREDERICK A. PURCHAS, OF McGRAW, NEW YORK.

CANDY BOX.

Application filed December 3, 1926. Serial No. 152,471.

This invention relates to candy boxes although it is of course to be understood that the device may be used as a receptacle for any desired articles or as a feature of window display, and I therefore do not limit myself to the particular use to which the device is to be put.

An object of the invention is to provide a box simulating a log cabin in appearance and having an improved lock controlling means for the cover of the box and improved means for stopping and starting the playing of a music box hidden from view and located preferably under the bottom of the box.

With this and other objects in view, the invention consists in certain novel features of construction and combinations and arrangements of parts, which will be more fully hereinafter described and pointed out in the claims.

In the accompanying drawings—

Figure 1 is a perspective view of my improved box;

Figure 2 is a view in vertical transverse section on the line 2—2 of Figure 1;

Figure 3 is a view, in horizontal section, of the box, the view being taken on the line 3—3 of Figure 4;

Figure 4 is a fragmentary view, partly in elevation and partly in section, of the upper portion of the front wall of the box and the cover illustrating the lock or catch and the means for controlling the same;

Figure 5 is a fragmentary view, mainly in elevation but partly in section, showing the lower portion of the front wall, illustrating the means for controlling the starting and stopping of the music box.

My improved box, as above stated, simulates in appearance a log cabin, and while the parts which go to make up the box are relatively small I shall use the term "log" to define the members which go to make up the walls of the box.

45 A represents the body of the box and 2 the cover, said cover simulating in appearance the roof of the cabin, and having fixed thereto a block 3' which registers with a block 4 on the body to simulate in appearance the chimney of the cabin. This top 2, which simulates in appearance the roof of the cabin, is made up in sections simulating split logs, as clearly indicated, and the front, rear and end walls of the box simulating the cabin structure are made up of min-

iature logs 3, the logs forming the front and rear of the box being recessed to cause them to interlock and form a body or structure, which in appearance as well as in construction, follows the lines of the well known log cabin.

My invention has particularly to do with the lock or catch for securing the cover in closed position, and the means for controlling the operation of this latch or catch and also with means for controlling the operation of a music box or other analogous device, said music box being indicated by the reference numeral 5, confined within the walls of the box and preferably secured to the bottom 6 of the box, said bottom being disposed appreciably above the lower ends of the side and end walls, as clearly shown in Figure 2.

The cover 2 constituting the top of the cabin is connected at its rear to the body of the cabin by hinges 7 so that they swing from the full line position shown in Figure 2 to the dotted line position of said figure. This top or cover 2 adjacent its forward edge is provided with a recess 8 having a metal plate or bar 9 across a portion of its lower end to receive the locking finger 10 of a catch 11.

This catch 11 is in the form of a lever pivoted between its ends to the upper log 3 of the front wall, as shown at 12, and this upper log 3 and the log 13 next below the same are provided with normally aligned recesses 14 to accommodate or house the catch and hide the same from view, so that no lock or catch is visible from the exterior of the box.

To avoid confusion I would have it distinctly understood that I employ the reference character 3 to indicate all of the logs of the walls of the cabin with the exception of certain logs which have a movement independent of the other logs, it being understood of course that the logs 3 are stationary and fixed, while those logs which shall be given other reference numerals have a movement which will be described.

The lower end of the catch lever is pivotally connected to the log 13, as shown at 15, and this log 13 has a longitudinal movement against the action of a coil spring 16 which is interposed between one of the end logs 3 and the wall 17 of a recess 18 in log 13.

This log 13 is however held against longitudinal movement by a log 19 constituting a portion of one end wall of the box. The log 19 is recessed, as shown at 20, so that when it is given a quarter turn the log 13 can be moved longitudinally, but when it is returned to its normal position it will hold the log 13 against longitudinal movement, as clearly shown at the left of Figure 4.

10. The parts are so arranged that when the cover is closed the catch 11 will snap into locked position. To release the catch, it is necessary to first turn the lock 19 and then impart a longitudinal movement to the log 13 which will cause the catch to swing to the dotted line position shown in Figure 4 and release the cover.

As above stated, the reference numeral 5 indicates a music or other sound creating mechanism, and I have not attempted to illustrate specifically any particular construction except to show a rotary member 21 which is caused to turn by the motor of the music box.

25. To control the stopping and starting of this music box, one of the front logs of the box, indicated by the reference numeral 22, is permitted a turning movement and is provided with a pin or crank arm 23 thereon, 30 which is movable into and out of the path of the device 21 so that when this pin is in the path of the device 21 it will stop the music box, and when moved into a position to free the rotary device 21 the music box 35 will play.

Various changes and alterations might be made in the general form of the parts described without departing from my invention and hence I do not limit myself to the 40 precise details set forth but consider myself at liberty to make such changes and alterations as fairly fall within the spirit and scope of the appended claims.

I claim:

45. 1. A box simulating a log cabin in appearance and including a body and a cover, the walls of said body comprising front, rear and end walls composed of superimposed logs, the logs at right angles to each other 50 having interengagement, a catch supported by the body and adapted to engage the cover, and one of the logs of the box operatively

engaging the catch and adapted to be moved to operate the catch.

2. A box simulating a log cabin in appearance and including a body and a cover, 55 the walls of said body comprising front, rear and end walls composed of superimposed logs, the logs at right angles to each other having interengagement, a catch supported by the body and adapted to engage the cover, one of the logs of the box operatively engaging the catch and adapted to be moved to operate the catch, and another of the logs of the box adapted to prevent or permit the 60 movement of the first-mentioned log.

3. A box simulating a log cabin in appearance and including a body and a cover, 70 the walls of said body comprising front, rear and end walls composed of superimposed 75 logs, the logs at right angles to each other having interengagement, a catch supported by the body and adapted to engage the cover, one of the logs of the box operatively engaging the catch and adapted to be moved to operate the catch, and another of the logs of the box adapted to prevent or permit the 80 movement of the first-mentioned log, and a spring holding the first-mentioned log in normal position, said spring and catch entirely hid from view.

4. A box of the character described, simulating in appearance a log cabin, and comprising a body and a hinged cover thereon, the walls of said body comprising front, 85 rear and end walls composed of superimposed logs, the logs at right angles to each other having interengagement, a pivoted catch located within a wall of the box operatively engaging the catch and adapted to 90 engage a member on the cover to hold the latter in closed position, a longitudinally movable log forming a portion of one wall of the box and connected to the catch to move the same to release position, a spring 95 holding said lock in normal position, and a second log at right angles to the first-mentioned log and adapted when turned to one position to prevent longitudinal movement of the first-mentioned log and when turned 100 to another position to permit said longitudinal movement.

FREDERICK A. PURCHAS.
